(57) **CLAIM**

The ornamental design of a hand held surgical instrument for
creating cavities in interior body regions, as shown and
described.

DESCRIPTION

FIG. 1 is a perspective view of a hand held surgical
instrument for creating cavities in interior body regions
showing our new design.

FIG. 2 is a bottom elevation view thereof.

FIG. 3 is a top elevation view thereof.

FIG. 4 is a right side elevation view thereof, the left side
being a mirror image thereof.

FIG. 5 is a front plan view thereof; and,

FIG. 6 is a back plan view thereof.
